DEAERATING FEED-WATER HEATER

Joseph F. Sebald, Bloomfield, N. J., assignor to
Worthington Pump and Machinery Corporation,
Harrison, N. J., a corporation of Delaware

Application October 3, 1944, Serial No. 557,018

12 Claims. (Cl. 261—36)

The present invention relates to apparatus for heating and deaerating liquids, and more particularly to a novel method of and means for treating water for boiler feed purposes and other services requiring practically oxygen-free water. The apparatus of the present invention is of the mixing type, as disclosed in U. S. Patent 2,308,719, and Patent 2,308,721, both of which issued January 19, 1943, in contradistinction to the "atomizing" and "tray" types of water treating apparatus known in the art. Steam jet deaerating apparatuses such as are shown in the foregoing patents embody two stages of heating and deaeration, the first or primary stage consisting of a spray type direct contact heater and deaerator, and the second or secondary stage consisting of a direct contact heater and deaerator of the steam jet eductor type.

An object of the invention is to provide an apparatus for heating and deaerating liquids, wherein means are provided for recirculating processed or partly processed effluent back through the apparatus to increase the overall time of contact of the liquid with conditions which produce completion of chemical reactions and increased deaeration.

Another object is to provide a steam jet feed-water heater of the multistage heating and deaerating type, wherein the construction is such as to effect deaeration with a minimum steam pressure drop between the incoming steam and the steam in contact with the deaerated water in the storage space, and in which means are provided for recirculating water from the storage or from predetermined secondary stages, either singly or simultaneously, back to the primary stage to obtain improved performance of the apparatus.

A further object is to provide a method of heating and deaerating water in which effluent is recirculated with incoming water to be treated in such manner as to obtain more effective deaeration and purification.

With these and other objects in view, as may appear from the accompanying specification, the invention consists of various features of construction and combination of parts, which will be first described in connection with the accompanying drawing, showing a deaerating feedwater heater of a preferred form embodying the invention, and the features forming the invention will be specifically pointed out in the claims.

The drawing represents a deaerating feedwater heater in accordance with the present invention.

Referring more particularly to the drawing, 55

the feedwater heater and deaerator shown therein comprises a shell 1 which is circular in cross section. The lower portion of this shell provides a storage space, as shown at 2, for storing the heated and deaerated water until it is removed for use. Water to be treated is caused to pass through a vent condenser 3 which is provided with the usual water inlet 4, water outlet 5, and vent 6 for expelling the non-condensable gases liberated in the process of deaeration. To the water outlet 5 is connected a pipe 7 which extends through the side 8 of the shell 1 and through which water flows from the condenser 3 to a spray head 9, the latter being located axially of the shell 1 and within the initial heating and deaerating chamber or compartment 10.

Within the shell 1 is mounted a horizontal partition or dished head 11 with its concavity facing down. The partition 11 is spaced from the top 12 of the shell 1 to provide a passage or chamber 13 adjacent the top, and the partition is of annular contour but of smaller diameter than the shell 1 to provide an annular passage 14 which places the initial heating and deaerating chamber 10 in communication with the passage 13. A depending flange 15 extends about the perimeter of the partition 11.

Water which enters the spray head 9 is sprayed therefrom through spring loaded valves or nozzles 16, of any suitable type, into the initial heating and deaerating chamber 10 and in the direction of the partition 11. The water emitted through the valves 16 forms fine particles in direct contact with the steam in the initial heating and deaerating chamber 10 and is heated to approximately steam temperature, in addition to being partially deaerated or degasified.

Beneath the partition 11 is positioned a laterally extending and downwardly inclining flange or partition 17, the latter being joined to the side 8 of the shell 1. The partition 17 is provided with a central opening 18 of smaller diameter than the partition 11, but in concentric relationship therewith. Water sprayed into the initial heating and deaerating chamber 10 falls into a collecting cone 19 beneath the partition 17. Much of the water impinging against the partition 11 is deflected laterally and then downwardly by the flange 15, as at 20. The water which is deflected downwardly by the flange 15 falls on the partition 17 and is directed into the collecting cone 19, so that all the falling water is directed into the collecting cone.

In addition to the first stage of heating and de-

aeration, as represented by the initial heating and deaerating chamber 10, the incoming water is caused to pass through two additional stages of heating and deaeration before it is delivered to the storage space 2; that is to say, through a second or intermediate stage 21, and a third or final stage 22. All three stages are connected in series relationship, so that the incoming water passes successively from the collecting cone 19 to second and third stages 21 and 22, respectively, and then to the storage space 2.

The collecting cone 19 includes an upper wall 23 of conical contour, a bottom wall 24 of the same contour, and a vertical annular wall 25 attached to the perimeters of the two walls 23 and 24. The wall 25 is arranged co-axially with the partition 17 and is of smaller diameter than the wall 8 of the shell 1 to provide an annular passage 26 for steam which flows upwardly from the chamber 27 of the second stage 21 of heating and deaeration to the initial heating and deaerating chamber 10. As will be noted by reference to the drawing, the walls 23 and 24 are spaced to provide a conical space or passage 28 for steam, which steam is admitted to the space 28 through tubes 29, the passages 30 in the tubes 29 placing the space 28 in communication with the chamber 31 of the third stage 22 of heating and deaeration.

Water in its passage from the second to the third stage of heating and deaeration falls into a collecting cone 32 arranged coaxially with the collecting cone 19. The collecting cone 32 comprises an upper conical wall 33, a bottom conical wall 34, and a vertical annular wall 35. The wall 33 is joined at its perimeter to the wall 8 of the shell 1 so that the chambers 27 and 31 of the second and third stages of heating and deaeration, respectively, are sealed one from the other, with exception of the passages 30 in the tubes 29. The walls 33 and 34 are spaced to provide a conical space or passage 36 for steam utilized for heating and deaerating the water, which steam may be derived from any suitable source, such as exhaust steam from an engine or steam from the bleeder stage of a steam turbine (not shown). This steam enters the space 36 through an inlet 37, the latter opening through the wall 35 of the collecting cone 32 and extending through the wall 8 of the shell 1.

The water which falls on the collecting cone 19 is further heated because of the steam circulating in the space 28, and this water, in its passage from the initial heating and deaerating stage to the second heating and deaerating stage, drains from the collecting cone 19 through a downtake pipe 38 which is coaxial with both collecting cones 19 and 32. An annular and upturned flange 39 is formed at the lower end of the downtake pipe 38, and a neck or pipe section 40 extends downwardly from the lower end of the wall 24 and into the annular cavity 41 defined by the upturned flange 39. The neck 40 is arranged concentrically of the downtake tube 38 and is of larger diameter than the latter to provide an annular passage 42 for the escape of steam from the space 28 in the collecting cone 19.

A cup-like member 43 is mounted beneath and coaxially with the downtake tube 38 which member includes an upstanding wall 44 arranged concentrically of the upturned flange 39. The wall 44 is of larger diameter than the upturned flange 39 to provide an annular escape passage 45 for water delivered to the compartment 46 defined by the member 43.

The upturned flange 39 and the neck 40 are of such relative diameters as to provide a passage 47 in continuation of the passage 42, the passage 47 being coaxial with the passage 45.

The wall 44 coacts with the neck 40 to provide a confined mixing or combining passage 48, with the passages 45 and 47 discharging upwardly into the confined mixing passage 48, so that the water and the steam passing upwardly through the passages 45 and 47, respectively, pass through the confined mixing passage 48 in parallel flow. A flare 49 is formed at the upper end of the wall 44 so that the confined mixing passage 48 includes a portion 50 which is of gradually increasing cross-sectional area in an upward direction.

Water collecting in the member 43 is drawn up into the confined mixing passage 48 by the educator action of the steam from the passage 47, and the mixture of steam and water flows at a high velocity through the confined mixing passage 48. The high velocity steam and water mixture emitted from the confined mixing passage 48 impinges on the wall 24 and a baffle 51 attached to this wall, the spray being deflected by the baffle 51 in a downward direction to the collecting cone 32.

Because of the flare 49, the mixture of steam and water flows from an area of high velocity to a gradually increasing area and reduced pressure. This results in further heating of the water to the temperature corresponding to the effective steam pressure, which is higher than the steam pressure in the initial heating and deaerating chamber 10. Only a small amount of the total steam is condensed in the confined mixing passage 48 since the water is virtually at saturated temperature. This allows nearly full flow of the steam to transmit sufficient velocity to the water to break it up into minute particles and promotes the final removal of oxygen and non-condensable gases. As the water and steam mixture enters the portion 50 of the confined mixing passage 48, a small amount of flashing occurs which further agitates the water particles and assists in water and gas separation prior to impingement on the baffle 51.

In passing the water stream and the steam stream emitted from the passages 45 and 47, respectively, through the confined mixing passage 48, a thermal-compression action is obtained which causes a thorough mixing of the steam and the water before they are projected into the lower pressure area for deaeration. By regulation of the relative areas of the passages 45 and 47, the quantity of steam and water may be proportionately controlled and regulated to meet the conditions of operation under which the apparatus is to work, and in accordance with the final temperature of the water desired.

The steam and non-condensable gases in their upward travel from the second stage of heating and deaerating break through the water film deflected by the baffle 51 and enter the initial heating and deaerating chamber 10 through the passage 26, the space between the upper end of the wall 25 and the partition 17, with the steam and non-condensable gases breaking through the water film spilling from the partition 17 into the collecting cone 19. Further heating and deaeration takes place in the initial heating and deaerating chamber 10, and part of the steam which enters this chamber is condensed and the remainder, together with the non-condensable gases, breaks through the water spray therein and flows upwardly through the passage 14 and a central opening 52 in the partition 11, into the space 13,

and into the inlet 53 leading to the vent condenser 3.

The steam condensed in the vent condenser 3 is returned to the initial heating and deaerating chamber 10 through a water sealed outlet 54, which condensate spills into the collecting cone 19 for delivery to the water flowing to the second stage of heating and deaeration.

To the lower end of the wall 34 is connected a downtake tube 55 which is provided with an upturned flange 56 at its lower end. A neck or tube 57 depends from the lower end of the wall 34 and is arranged concentrically of the downtake tube 55, with the two tubes of such relative diameters as to provide an annular passage 58 for the escape of steam from the space 36 in the collecting cone 32. The lower end of the neck 57 extends into the annular cavity 59 defined by the flange 56 and coacts with the latter to provide an annular steam passage 60 in continuation of the passage 58.

A cup-like member 61 is mounted in the chamber 31 and includes an annular upstanding wall 62 arranged concentrically of the upturned flange 56. The wall 62 and the upturned flange 56 are of such relative diameters as to provide an annular passage 63 for the escape of water from the chamber 64 defined by the member 61. In addition, the wall 62 is of such diameter with respect to the neck 57 as to provide an annular confined mixing or combining passage 65 which is coaxial with both passages 60 and 63, the passages 60 and 63 discharging upwardly in parallel flow into the confined mixing passage 65. A flare 66 is formed at the upper end of the wall 62 so that the confined mixing passage 65 includes a portion 67 of progressively larger cross-sectional area in an upward direction. The high velocity steam and water mixture emitted from the confined mixing passage 65 impinges on the wall 34 and a baffle 68 attached to that wall, the spray being deflected by the baffle in a downward direction to the storage space 2.

The steam and non-condensable gases in their upward travel from the chamber 31 of the third or final stage of heating and deaeration break through the water film deflected by the baffle 68 and pass to the second or intermediate stage of heating and deaeration through the passages 30 in the tubes 29. It will thus be seen that the structures defining the second and third stages of heating and deaeration are generally identical. The steam enters the third stage of heating and deaeration and is first used as the heating and deaerating medium in the final stage of deaeration. From the third stage, the steam enters the second or intermediate stage for the same purpose, after which the steam flows to the initial heating and deaerating chamber 10 where initial heating and partial deaeration of the incoming water is effected.

While the structures of the second and third stages of heating and deaeration are similar in mechanical design, the steam passages 58 and 60 are larger than the corresponding passages 42 and 47 of the second stage of heating and deaeration. However, the relative areas of the passages 58 and 60 may be changed with respect to each other and with respect to the passages 42 and 47 to meet different operating conditions.

In operation, the deaerator herein shown and described incorporates a primary or initial stage of the spray type of heating and deaeration followed by at least two stages of direct contact

heating and deaeration. The primary stage performs the major portion of the heating and deaeration and heats the water to within a very few degrees of the steam temperature corresponding to the pressure in that stage of the apparatus.

The second stage of direct contact heating and deaeration heats the water essentially to steam temperature corresponding to pressure in the compartment 27, in addition to maintaining a highly effective scrubbing action of the steam and water to effect final or complete deaeration. Because of the necessity for maintaining the high velocity scrubbing action in this stage, a considerable pressure drop takes place between the incoming steam to the apparatus and the steam in the chamber 27, which results in a loss of available sensible heat and may be a source of uneconomical operation or may disturb the normal heat balance of the power plant system. Such a temperature depression is objectionable when the deaerating apparatus is applied with steam from the bleeder stage of a steam turbine.

In order to eliminate the objectionable temperature depression which takes place in the second stage of heating and deaeration, the third stage of heating and deaeration incorporated in the present apparatus is structurally similar to the structure of the second stage, but is designed to produce the heating effect with a lesser degree of scrubbing action and turbulence to thereby heat the water only essentially to that of steam temperature in the third stage of heating and deaeration. Because of the liberal steam passages involved, the pressure drop between the incoming steam and the steam in the compartment 31 is extremely small, and the loss of sensible heat is minimized. Of course, a certain amount of deaeration will be effected although it will be minor as compared to the deaerating qualities of the primary direct contact stage as well as the second stage of direct contact heating and deaeration. While two stages are illustrated in addition to the primary stage, additional stages of direct contact heating and deaeration may be added.

It will thus be seen that the invention herein shown and described embodies stages of heating and scrubbing which result in prolonged mixing and time of contact at elevated temperatures to a degree whereby more effective degasification and purification are produced. Thus the chemical reaction between the carbonates contained in the water and the added chemical compounds which may be employed in the treating process, for example, may be forced to completion by prolonged intimate mixing of the components at elevated temperatures, such as are necessary to increase the rate of reaction, and that one or more of the gaseous products of the reaction may be removed from the water being processed, and the reaction made irreversible to approach completion.

Means are provided for recirculating the fluid which has been processed through the apparatus or partly processed back to the initial stage of heating and deaeration. Pipes 69 and 70 communicate with the bottom portions of the cups 43 and 61, respectively, and a pipe 71 leads into the bottom of the storage 2. All these pipes are connected with the inlet eye 72 of a power driven centrifugal pump 73, which may be of any approved type. Control valves 74, 75, and 76 are interposed in the pipes 69, 70, and 71, respectively. To the discharge 77 of the pump 73 is connected a pipe 78 which leads into the pipe 7 for deliver-

ing processed or partly processed water to the incoming water to be treated.

Because of the valves 74, 75, and 76, finally treated effluent from the storage 2 or effluent from the two secondary stages of heating and deaeration may be recirculated individually or simultaneously back to the primary stage. Such recirculation of the effluent increases the overall time of contact of the liquid with conditions which produce completion of chemical reactions and increased deaeration. The recirculated effluent is subjected to an additional treatment by increasing its time of contact in the preceding stage, which increases the amount of scrubbing and deaeration. Such recirculation also increases the combined temperature of the liquid entering the preceding stages which increases the rate of chemical action in the preceding stages. Recirculation also lends itself to more effective removal of free carbon dioxide and ammonia which are, under certain conditions, extremely difficult to remove in conventional types of deaerating apparatus.

A valve 79 is interposed in the pipe 78 so that the entire recirculation system may be isolated from the apparatus.

It will be understood that the invention is not to be limited to the specific construction or arrangement of parts shown, but that they may be widely modified within the invention defined by the claims.

What is claimed is:

1. In a liquid heating and deaerating apparatus, an initial treatment chamber, means for introducing liquid to be treated to said chamber, a plurality of supplementary treating chambers, confined mixing passages for liquid and steam including means for delivering liquid from said initial treatment chamber to the successive confined mixing passages, said confined mixing passages each discharging liquid and steam into one of said supplementary treating chambers, means for delivering steam to one of said confined mixing passages and successively to the remainder of said plurality of mixing passages and said initial treatment chamber, and means for recirculating finally treated liquid back to the initial treatment chamber.

2. In a liquid heating and deaerating apparatus, an initial treatment chamber, means for introducing liquid to be treated to said chamber, a plurality of treatment chambers arranged in series relationship to cause liquid to be treated to flow from the initial treatment chamber to and through said plurality of treatment chambers, confined mixing passages for steam and liquid including means for delivering liquid to the successive confined mixing passages, means for introducing steam to one of said confined mixing passages and successively to the remainder of said plurality of mixing passages and to the initial treatment chamber, and means for recirculating partially treated liquid back to the initial treatment chamber.

3. A water heating and deaerating apparatus comprising a shell provided with an initial treatment chamber and a storage chamber for treated water, means for introducing water to be treated into said chamber, an intermediate treatment chamber, a first confined mixing passage for water and steam including means for delivering water thereto from said initial treatment chamber, said first confined mixing passage discharging water and steam into said intermediate treatment chamber, a final treatment chamber defined

in part by said storage chamber, a second confined mixing passage for water and steam including means for delivering water thereto from said intermediate treatment chamber, said second confined mixing passage discharging water and steam into said final treatment chamber and the storage chamber, means for delivering steam to said second confined mixing passage, means for delivering steam from said final treatment chamber to said first confined mixing passage, means for delivering steam from said intermediate treatment chamber to said initial treatment chamber, means for recirculating partially treated water back to the initial treatment chamber, and means for recirculating finally treated water back to the initial treatment chamber.

4. A water heating and deaerating apparatus comprising a shell provided with an initial treatment chamber and a storage chamber for finally treated water, means for introducing water to be treated into said chamber, an intermediate treatment chamber, a first confined mixing passage for water and steam including a collecting cone for delivering water to the confined mixing passage from said initial treatment chamber, said first confined mixing passage discharging water and steam into said intermediate treatment chamber, a final treatment chamber defined in part by said storage chamber, a second confined mixing passage for water and steam including a collecting cone for delivering water to said second confined mixing passage from said intermediate treatment chamber, said second confined mixing passage discharging water and steam into said final treatment chamber and the storage chamber, means for delivering steam to said second confined mixing passage, means for delivering steam from said final treatment chamber to said first confined mixing passage, means for delivering steam from said intermediate treatment chamber to said initial treatment chamber, means for recirculating partially treated water back to the initial treatment chamber, and means for recirculating finally treated water back to the initial treatment chamber.

5. A water heating and deaerating apparatus comprising a shell provided with an initial treatment chamber and a storage chamber for treated water, means for introducing water to be treated into said chamber, an intermediate treatment chamber, a first confined mixing passage for water and steam including a collecting cone for delivering water to the confined mixing passage from said initial treatment chamber, said first confined mixing passage discharging water and steam into said intermediate treatment chamber, a final treatment chamber defined in part by said storage chamber, a second confined mixing passage for water and steam including a collecting cone for delivering water to said second confined mixing passage from said intermediate treatment chamber, said second confined mixing passage discharging water and steam into said final treatment chamber and the storage chamber, means for delivering steam from a single source to both confined mixing passages and said initial treatment chamber, means for recirculating partially treated water back to the initial treatment chamber, and means for recirculating finally treated water back to the initial treatment chamber.

6. In a water heating and deaerating apparatus, an initial treatment chamber, means for in-

roducing water to be treated into said chamber, an intermediate treatment chamber, a first confined mixing passage for water and steam including means for delivering water thereto from said initial treatment chamber, said first confined mixing passage discharging water and steam into said intermediate treatment chamber, a final treatment chamber, a second confined mixing passage for water and steam including means for delivering water thereto from said intermediate treatment chamber, said second confined mixing passage discharging water and steam into said final treatment chamber, means for delivering steam to said second confined mixing passage in separated heat transfer relationship to the water flowing to the second confined mixing passage, means for delivering steam from said final treatment chamber to said first confined mixing passage in separated heat transfer relationship to the water flowing to the second confined mixing passage, means for delivering steam from said intermediate treatment chamber to said initial treatment chamber, means for recirculating finally treated water back to the initial treatment chamber, and means for recirculating partially treated water from points adjacent the respective confined mixing passages back to the initial treatment chamber.

7. In a water heating and deaerating apparatus, an initial treatment chamber, means for introducing water to be treated into said chamber, an intermediate treatment chamber, a first confined mixing passage for water and steam including a collecting cone for delivering water to the first confined mixing passage from said initial treatment chamber, said first confined mixing passage discharging water and steam into an intermediate treatment chamber, a final treatment chamber, a second confined mixing passage for water and steam including a collecting cone for delivering water to said second confined mixing passage from said intermediate treatment chamber, said second confined mixing passage discharging water and steam into said final treatment chamber, means for delivering steam to said second confined mixing passage in separated heat transfer relationship to the water flowing to the second confined mixing passage, means for delivering steam from said final treatment chamber to said first confined mixing passage in separated heat transfer relationship to the water flowing to the first confined mixing passage, means for delivering steam from said intermediate treatment chamber to said initial treatment chamber, means for recirculating finally treated water back to the initial treatment chamber, and means for recirculating partially treated water back to the initial treatment chamber.

8. In a water heating and deaerating apparatus, an initial treatment chamber, means for introducing water to be treated into said chamber, an intermediate treatment chamber, a first confined mixing passage for water and steam including a collecting cone for delivering water to the first confined mixing passage from said initial treatment chamber, said first confined mixing passage discharging water and steam into said intermediate treatment chamber, a final treatment chamber, a second confined mixing passage for water and steam including a collecting cone for delivering water to the second confined mixing passage from said intermediate treatment chamber, said second confined mixing passage discharging water and steam into said

final treatment chamber, means for delivering steam to said second confined mixing passage in separated heat transfer relationship to the water flowing through said second mentioned collecting cone to said second confined mixing passage, means for delivering steam from said final treatment chamber to said first confined mixing passage in separated heat transfer relationship to the water flowing through said first-mentioned collecting cone to said first confined mixing passage, means for delivering steam from said intermediate treatment chamber to said initial treatment chamber, valve controlled means for recirculating partially treated water back to the initial treatment chamber, and valve controlled means for recirculating finally treated water back to the initial treatment chamber.

9. A water heating and deaerating apparatus comprising an initial treatment chamber, means for introducing water to be treated into said chamber, an intermediate treatment chamber, a first confined mixing passage for water and steam including means for delivering water thereto from said initial treatment chamber, said first confined mixing passage discharging water and steam into said intermediate treatment chamber, a final treatment chamber, a second confined mixing passage for water and steam including means for delivering water thereto from said intermediate treatment chamber, said second confined mixing passage discharging water and steam into said final treatment chamber, means for delivering steam to said second confined mixing passage in separated heat transfer relationship to the water flowing to the second confined mixing passage, said final treating chamber being sealed from said intermediate treatment chamber, means defining passages for delivering steam from said final treatment chamber to said first confined mixing passage in separated heat transfer relationship to the water flowing to the first confined mixing passage, means defining an annular passage for delivering steam from said intermediate treatment chamber to said initial treatment chamber, means for recirculating partially treated water back to said first-mentioned means, and means for recirculating finally treated water back to said first-mentioned means.

10. In a liquid heating and deaerating apparatus, an initial treatment chamber, means for introducing liquid to be treated to said chamber, a plurality of supplementary treating chambers, confined mixing passages for liquid and steam including means for delivering liquid from said initial treatment chamber to the successive confined mixing passages, said confined mixing passages each discharging liquid and steam into one of said supplementary treating chambers, means for delivering steam to one of said confined mixing passages and successively to the remainder of said plurality of mixing passages and said initial treatment chamber, and means for recirculating partially treated liquid back to the initial treatment chamber.

11. A water heating and deaerating apparatus comprising an initial treatment chamber, means for introducing water to be treated into said initial treatment chamber, a first confined passage for water and steam including means for delivering water thereto from said initial treatment chamber, said first confined mixing passage discharging water and steam into said intermediate treatment chamber, a final treatment chamber, a second confined mixing passage for water and steam

steam including means for delivering water thereto from said intermediate treatment chamber, said second confined mixing passage discharging water and steam into said final treatment chamber, means for delivering steam to said second confined mixing passage in separate heat transfer relationship to the water flowing to the second confined mixing passage, said final treating chamber being sealed from said intermediate treatment chamber, means defining passages for delivering steam from said final treatment chamber to said first confined mixing passage in separate heat transfer relationship to the water flowing to the first confined mixing passage, means defining an annular passage for delivering steam from said intermediate treatment chamber to said initial treatment chamber, and means for recirculating partially treated water back to said first-mentioned means.

12. A water heating and deaerating apparatus comprising an initial treatment chamber, means for introducing water to be treated into said initial treatment chamber, a first confined passage for water and steam including means for delivering water thereto from said initial treatment

10
15

chamber, said first confined mixing passage discharging water and steam into said intermediate treatment chamber, a final treatment chamber, a second confined mixing passage for water and steam including means for delivering water thereto from said intermediate treatment chamber, said second confined mixing passage discharging water and steam into said final treatment chamber, means for delivering steam to said second confined mixing passage in separate heat transfer relationship to the water flowing to the second confined mixing passage, said final treating chamber being sealed from said intermediate treatment chamber, means defining passages for delivering steam from said final treatment chamber to said first-confined mixing passage in separate heat transfer relationship to the water flowing to the first confined mixing passage, means defining an annular passage for delivering steam from said intermediate treatment chamber to said initial treatment chamber, and means for recirculating treated water back to said first-mentioned means.

JOSEPH F. SEBALD.
